CIRCUIT BREAKER WITH MAGNETIC ARC
EXTINGUISHING MEANS

Gerhard W. Peters, Akron, Ohio

Application July 8, 1943, Serial No. 493,847

12 Claims. (Cl. 200—147)

2

1 My invention relates to means and methods for controlling an electric arc or electron discharge between electrodes or contacts in an electrical circuit, and more particularly to such means and methods for extinguishing an arc or electron discharge between electrodes or contacts of a circuit breaker or current interrupter.

Upon the establishment of an uncontrolled arc or electron discharge between two electrodes or contacts in an electrical circuit, the characteristic is such that it suddenly grows into a full arc which comprises an intensely brilliant core surrounded by a cooler region of flaming gases. The arc occurs with explosive suddenness and the accompanying flame which is one of the arc phenomena may, in many instances, propagate itself to great length and cross-sectional area compared with the arc core proper. Consequently, the flame itself must be ruptured as well as the arc discharge to interrupt the circuit.

In the prior art circuit breakers, attempts have been made to house or confine the flame by walls or barriers to prevent injury to adjacent parts and to prevent the flame from bridging metal parts and making a short circuit in the contactor. The flame therefore must be dealt with concurrently with the arc proper.

My invention utilizes the reaction between the field of the arc or electron discharge extending from one electrode to the other and a magnetic field to control the arc structure in a new and novel manner, and is applicable to any device where it is found desirable or necessary to control the current flowing between spaced electrodes or to rupture the current flowing between spaced electrodes such as found in circuit breakers, contactors and other interruptors of electrical current.

My invention makes a radical departure from all the prior art devices and principles embodied therein, by utilizing a magnetic field of such strength and pattern as to modify the structure of the arc and to substantially keep it from growing beyond control. The evolution of flame is prevented; the explosive sound usually accompanying the rupturing of flaming arcs is absent; the usual provisions for dealing with the destructive and dangerous flame are unnecessary; and the burning of the contacts is greatly reduced and their life accordingly prolonged.

The strength and the pattern of my magnetic field is such as to modify the arc and give it the appearance of a flow with substantially no flaming gases. The resistance of the arc may be varied without materially stretching it by chang-

ing the strength of the magnetic field and complete control is maintained over the structure of the arc to keep it from growing. My device may be characterized as an inhibitor of ionization which prevents the arc from growing rather than a de-ionizer which allows the arc to grow to a full arc after which de-ionization occurs to extinguish the arc and the resultant flame.

It is accordingly among the objects of my invention:

10 To provide generally an improved means and method utilizing a magnetic field for confining the arc or electron discharge between the contacts or electrodes;

15 To provide for establishing a strong magnetic field to influence the arc or electron discharge between the interrupting electrodes and to inhibit ionization which keeps the discharge from growing;

20 To provide for controlling the structure of the arc by a strong magnetic field;

To modify the arc and give it substantially the appearance of a glow with no flaming gases;

25 To provide for increasing the resistance of the arc without materially increasing the length thereof;

30 To provide means to control a discharge or arc from the moment it begins to form so as to resist the growth of the discharge and simultaneously exert the necessary forces to extinguish said discharge;

35 To provide for causing each end of the electron discharge which exists between two electrodes to be forced to remain substantially on the surface of the interrupting electrodes by employing a magnetic field of such strength and pattern as to resist the ends of the discharge from leaving the contacts, and for causing the discharge to be constrained substantially within the volume of space embraced between the electrodes;

40 To provide for directing the magnetic flux in a funnel-like fashion through one electrode, the space between the electrodes and the other electrode;

45 To provide for focusing the magnetic flux so that it will pass through the discharge space between the electrodes in a funnel-like fashion, in such a position that the axis of the contacts is substantially parallel with the axis of the funnel-like flux pattern, or that both axes substantially coincide with each other;

50 To direct flux in a funnel-like fashion with one of the electrodes positioned at the throat of the funnel-like flux lines and with the other electrode positioned within the rim of the funnel-like

flux lines, wherein a discharge which exists between the electrodes is magnetically restrained substantially within the boundary of the funnel-like flux lines;

To provide for causing each end of the discharge which exists between two electrodes to be forced toward the central portions of the electrodes;

To provide and utilize a magnetic field, that directs the flux of sufficient strength in the discharge space between the electrodes at an angle thereacross, whereby the angularly directed flux has strong vertical and horizontal components of flux which react with the flux produced by the discharge itself to immediately extinguish the discharge without the necessity of removing the discharge from the space between the interrupting electrodes;

To provide a means and method for extinguishing a discharge drawn between the contacts or electrodes, which progressively transversely constricts the discharge inwardly from all sides toward the central axis of the discharge.

To provide a combination of discharge enclosing chamber, means for producing a magnetic flux in a funnel-like pattern inside the discharge enclosing chamber, and means for drawing a discharge between two electrodes inside the chamber and within the limits of the funnel-like flux pattern, wherein the discharge which exists between the electrodes is substantially kept from contacting side wall portions of the chamber;

To provide in the arc chamber a recess having an insulating surface disposed transversely of a path between the stationary contact and the opening in which the movable contact moves.

To provide for keeping the arc on the contacts away from the recess and prevent deposits created by the arc from lodging upon the insulating surface in the recess and establishing a conductive path between the stationary contact and the opening in which the movable contact moves.

To provide for utilizing the magnetic material of part of the magnetic circuit as a cooling enclosing chamber for the discharge;

To provide for substantially enclosing the electrodes between which a discharge is drawn in an enclosing chamber and for directing a magnetic flux of a funnel-shaped pattern across the discharge space between the electrodes;

To provide for substantially enclosing the electrodes between which a discharge is drawn in a shell-like metal housing, whereby the shell-like metal housing constitutes part of the magnetic circuit;

To provide for electrically insulating one of the magnetic pole means of the magnetic circuit from the electric circuit, when construction is such that both poles may come into contact with the discharge.

Other objects and a fuller understanding of my invention may be had by referring to the following description and claims, taken in conjunction with the accompanying drawings, in which:

Figure 1 is a longitudinal sectional view of a structure embodying my invention;

Figure 2 is a cross-sectional view taken from the line 2-2 of Figure 1, with parts beyond the section plane omitted;

Figure 3 is an enlarged view of the magnetic circuit showing the disposition of the magnetic flux which cuts across the electron discharge space at an angle and produces strong vertical and horizontal components of flux which react

with the flux produced by the discharge to immediately extinguish the discharge;

Figure 4 is a cross-sectional view of a double-break type of circuit interrupter or contactor embodying the features of my invention;

Figure 5 is a fragmentary view of Figure 4 showing a modified form of the magnetic circuit;

Figure 6 is a view of a further modified form of the outer shell part of the magnetic circuit;

Figure 7 is a view similar in general to Figure 1 but illustrating a modification of the magnetic circuit;

Figure 8 is a cross-sectional view taken from the plane 8-8 of Figure 7, with parts beyond the section plane omitted;

Figures 9 and 10 are views illustrating modifications in the central core construction of my invention; and

Figures 11 and 12 are views similar in general to Figure 1, but illustrating modifications utilizing permanent magnets instead of the electromagnets for producing a strong magnetic field.

With reference to Figure 1 of the drawings, I illustrate a circuit interrupting device having a pair of interrupting electrodes 20 and 21 for interrupting the current flowing through the load which is energized from the supply conductors 17 and 18. The reference character 20 represents the stationary electrode and the reference character 21 represents the movable electrode which may be actuated by any suitable actuating mechanism such as designated by the reference character 19. To improve the interrupting property of the electrodes, each may be provided with contact tips or members which may be made of silver or of any other arc resisting material. The contact tip for the stationary electrode 20 is designated by the reference character 22 and the contact tip for the movable electrode 21 is designated by the reference character 23. The stationary and the movable electrodes may be made of copper or any other metal having a high electrical conductivity. Besides possessing a high electrical conductivity, the movable electrode 21 is preferably non-magnetic.

As illustrated in the drawings, the stationary electrode 20 may be supported by a centrally arranged post 24 carried by a suitable insulated block or panel 26. The lower end of the post 24, as shown in the drawings, is provided with a reduced end provided with threads to which the stationary electrode 20 may be threadably connected. While I have illustrated the stationary electrode 20 as being threadably connected to the post 24, it is to be understood that my invention contemplates the securing of the stationary electrode 20 in relative position to the post 24 by any other suitable means. The lower end of the post 24 where it meets with the threads is provided with a shoulder 27. A lock washer 25 may be interposed between the shoulder 27 and the stationary electrode 20 to firmly secure the stationary electrode 20 upon the post 24.

The upper end of the post 24, as shown in Figure 1 of the drawings, is provided with an integral stud extension 28 which passes through an opening in the insulated block or panel 26. The lower side of the insulated block or panel 26 may be somewhat recessed to receive a circular metal plate 29. The integral stud extension 28 passes through an opening within the circular metal plate 29. The diameter of the integral stud extension 28 is smaller than the post proper to provide a shoulder 34 that rests against the circular metal plate 29, so that when the nut 35

which threadably engages the upper end of the stud extension 28 is firmly turned down, the post 24 is rigidly connected to the insulated block or panel 26. To the uppermost end of the stud extension 28 is attached a terminal clip 33 which may be electrically connected to the supply conductor 17. The terminal clip 33 may be secured to the stud extension 28 by means of the nuts 31 and 32.

Mounted upon the underneath side of the insulated block or panel 26 is an insulated housing 36 which may be secured to the insulated block or panel 26 by any suitable means. The insulated housing 36 is provided with a deep cylindrical recess 37 to receive a cylindrical tubular body 38 having an annular head 39 provided with an opening 40 through which the movable electrode 21 moves. The upper annular end of the tubular body 38 registers with the peripheral edge of the circular metal plate 29. The insulated housing 36 is provided with an opening 41 which is slightly smaller in diameter than the opening 40 in the annular head 39 so that the opening 41 may constitute a guide for the movable electrode 21 as it is moved relative to the stationary electrode 20 by the actuating mechanism 19. By means of this construction, the movable electrode 21 does not make electrical contact with the annular head 39 of the tubular body 38, as the electrode is moved in and out of the opening 40.

The tubular body 38 having the annular head 39 and the circular metal plate 29 constitute a shell-like metal housing for the interrupting electrodes 20 and 21 and the side clearance between the movable electrode 21 and the opening 41 is relatively small to make a relatively tight arc or electron discharge enclosure chamber. The post 24, the circular metal plate 29, the tubular body 38 having the annular head 39, constitute a magnetic circuit in which the post 24 comprises one pole portion and in which the annular head 39 constitutes the other pole portion. The lines 43 in Figure 3 illustrate generally the direction of the lines of flux which pass between the two pole portions. The separation of the movable electrode 21 from the stationary electrode 20 occurs in the air gap between these two magnetic pole portions whereby a discharge between the separating electrodes is controlled by the flux passing between the two pole portions. The flux for the magnetic circuit may be set up by means of a magnetizing coil 42 which surrounds the post 24 and which may be energized by the supply conductors 17 and 18. In my invention I provide a strong flux field which controls the structure of the discharge. The flux which is established by the magnetizing coil 42 and which flows between the two pole portions may be characterized as funnel-shaped or fountain-shaped and passes at an angle across the space between the stationary electrode 20 and the movable electrode 21 and cuts the electron discharge which extends between the electrodes at an angle to immediately interrupt the discharge. The axis of the funnel-like flux pattern is preferably made substantially parallel with the axis of the electrodes. Both axes may substantially coincide with each other. The flux pattern has a strong vertical component of flux and a strong horizontal or radial component of flux which react with the flux produced by the discharge to control the structure of the discharge. The flux density is the greatest toward the outside of the funnel-like pattern, as illustrated by the heavy lines in Figure 3.

I have discovered that a strong magnetic flux

field having a funnel-like pattern is very effective in interrupting the discharge between the interrupting electrodes. In contro-distinction with prior art devices, my invention appears to inhibit the reproduction of ions which prevents the arc from growing into a full arc with flaming gases. In all of the tests which have been made upon my invention with a standing discharge maintained for observation and test purposes, the load current may be varied by changing the excitation of the magnetizing coil 42. With a weak field or with substantially no field at all the discharge appears to have the characteristic of a full arc with flaming gases, and since the arc is uncontrolled it generally is inclined to loop or bulge outwardly to one side of the spaced contacts, stretching itself to a length many times the distance between the spaced contacts and going through many queer twisting and bending movements of an indescribable nature. As the magnetic field is strengthened by increasing the excitation of the magnetizing coil 42, the standing arc goes through a state of conversion and approaches the appearance of a glow discharge with substantially no flaming gases while at the same time decreasing in length and drawing inwardly toward the center of the volume of space between the contacts. As the arc is drawn inwardly, it appears to "stiffen up" by the controlled action of the increased flux, causing the bulging and looping characteristics of the uncontrolled arc to disappear. As the magnetic field is further increased, the arc moves or is drawn further inwardly toward the central portion of the contacts and the glow-like appearance becomes darker and the arc finally disappears.

The last thing that one can observe upon the disappearance of the discharge is a glow at one end of the discharge which is apparently the cathode glow. Prior to the disappearance of the cathode glow, one can observe a glow at the other end of the discharge which is apparently the anode glow. A dark column appears to exist between the cathode glow and the anode glow. With a strong magnetic field, the standing arc when observed by the eyes of an observer gives the appearance of a cone or of the frustum of a cone as explained in my co-pending application, Serial No. 493,848, filed July 8, 1943. The base of the cone or of the frustum of the cone is on the stationary electrode 20. The apex of the cone points toward the movable electrode 21. The sides of the frustum of the cone lean inwardly with the cut-off end of the frustum terminating at the movable electrode 21. The cone-shaped discharge appears when the supply conductor 17 is positive and when the supply conductor 18 is negative, and the frustum of the cone-shaped discharge appears when the polarity of the conductors is reversed. High speed pictures when shown at low speed or at standstill, reveal that the glow discharge is in the form of a line or an element of the cone or of the frustum of the cone which is whirled or spun around by the magnetic field, thus appearing to the eyes, because of the speed of rotation, as a cone or a frustum of a cone. With the cone-shaped arc, the end of the arc line which clings to or contacts the movable electrode 21 remains substantially in one place upon the surface of the movable electrode and usually in the central region thereof with the other end of the arc line which contacts the stationary electrode swinging or whirling around in substantially a circle spaced inwardly at a distance from the peripheral edge of the stationary electrode. With the frustum of a

7
cone-shaped arc, one end of the arc discharge line spins or whirls around the peripheral edge of the stationary electrode 20 with the other end spinning around the movable electrode 21 at a distance spaced inwardly from the peripheral edge thereof.

The frustum of the cone-shaped arc sometimes approaches the shape of a cylinder with both ends of the arc spinning or whirling around the peripheral edges of the electrodes. Sometimes the discharge line or arc which is whirled or spun around takes the form of a spiral, but ordinarily the spiral is caused to straighten out in which case the arc extends substantially in a straight line between the separated electrodes. Accordingly, with a strong magnetic field, the ends of the discharge line are constrained to remain substantially on the surface of the electrodes and the discharge line itself is forced to remain substantially within the volume of space embraced between the separated electrodes. Sometimes the discharge or arc line, under the condition when a frustum of a cone or a cylinder is formed, may bulge or spiral outwardly a little with its ends clinging upon the electrodes or upon the side edge of the electrodes. In this application the expression "substantially within the volume of space embraced by the separated electrodes" includes an increased volume of space which may have a diameter substantially twenty (20%) percent greater than the diameter of the electrodes.

While one would ordinarily expect the resistance of the arc to decrease as the length of the arc is decreased, yet in my invention the reverse is true in that as the length of the arc is decreased by the application of a strong magnetic field, the resistance is increased. The resistance of the arc line or discharge when it passes from one of the spaced contacts to the other in substantially a straight line, as it does in the case of the cone or the frustum of a cone, is more than the resistance of a long or looping uncontrolled arc under the action of a weak field. Accordingly, the flow of the load current may be varied with a standing arc by changing the magnetic field strength. The increase in resistance appears to result from the fact that as the magnetic field is increased, the cross-sectional area of the arc line becomes smaller, decreasing to a relatively thin line arc or discharge. That is to say, the cross-sectional area of the discharge line is restricted from all sides inwardly toward the axis of the discharge line and the resistance can be made so high that the potential across the separated electrodes cannot maintain the flow of current therethrough. As the discharge line approaches the point of extinguishment, the whirling or spinning of the line substantially dies down and sometimes appears to remain substantially stationary just prior to its disappearance. The extinguishment of the discharge is not accompanied by a sudden explosiveness as usually accompanies the rupture of a flaming arc. The evolution of the flame is prevented and the burning of the contacts is greatly reduced.

In actual circuit breaker operation, the contacts separate very rapidly and the design and the size of the parts are such that the arc is immediately extinguished upon the rapid opening of the contacts. A person viewing the formation and interruption of the arc under rapidly separating contacts observes only a foreshortened arc, which gives the impression that the foreshortened arc is substantially extinguished be-

fore the contacts reach their full open position. Thus, a point is reached in the movement of the separation of the contacts where the arc disappears before the contacts are fully separated, the contacts continuing their separating movement with no arc therebetween. In other words, the arc line does not appear to continue to extend between the two separating contacts for the entire movement of the separation, but appears 10 to be cut off before the contacts are fully separated. With my invention it is not necessary to provide any special features in the actuating mechanism 19 to cause the movable electrode to be separated from the stationary electrode more rapidly than in the make-and-break contactors of common practice, nor is it necessary to separate the electrodes a greater distance than is found in common practice, to effect interruption 15 of the arc while the electrodes are moving apart.

20 The tubular body 38 shields the discharge between the two electrodes in such a manner that magnetic disturbances outside the enclosing chamber will not affect the discharge and cause it to move off the interrupting electrodes. In 25 addition, any movement of air outside the metal enclosing chamber will not come in contact with the discharge and cause it to move out of the space between the interrupting electrodes. The air which displaces the moving electrode 21 will flow into the space between the separating electrodes approximately equal from all sides of the electrodes, thus tending to centralize the discharge toward the center of the space between the electrodes. Inasmuch as the clearance between the opening 41 and the movable electrode 21 is relatively small the enclosing chamber acts 30 as a pressure chamber which aids in extinguishing the electron discharge. The pressure within the chamber is relatively equal in all directions from the discharge and accordingly there is substantially no unbalanced pressures which would 35 tend to move the ends of the discharge off the electrodes and from the volume of space between the electrodes.

40 45 In Figure 4 I illustrate a cross-sectional view of a double-break type of circuit breaker or contactor embodying the features of my invention, and corresponding parts are represented by the same reference characters as those found in Figure 1. In Figure 4 the movable electrodes 21 are connected together by a bridging member 47 and are simultaneously actuated by the actuating mechanism 19 for interrupting the circuit between the supply conductors 17 and 18. The 50 magnetizing coils in Figure 4 are energized by the load current and bear the reference character 44. As illustrated, the lower ends of the magnetizing coils 44 are connected to the electrodes 20 by means of clips 45 which are interposed between the electrodes 20 and the lock washers 25. The insulated block or panel 26 and the insulated housing 36 are suitably connected together and are in turn suitably mounted upon a bracket 48 which may be employed to fasten 55 the double-break type of contactor upon a suitable stationary support. The upper annular ends of the tubular body 38 are electrically insulated from the circular metal plates 29 by means of a sheet of insulating material 46 which 60 is disposed between the insulated block or panel 26 and the insulated housing 36. One purpose of the sheet of insulating material 46 is to electrically insulate the annular head 39 of the tubular body 38 from the post 24 and the electrode 65 70 75 20. With the annular head 39 so insulated, all

tendency for the electron discharge or arc to strike between the movable electrode 21 and the annular head 39 and by-pass current from flowing through the electrode 20, is positively precluded. In Figure 1 I do not show the annular head 39 as being electrically insulated from the post 24 and the electrode 20 as I find that the discharge under the influence of a strong magnetic field does not strike upon the annular head 39 as the movable electrode 21 is moved away from the stationary electrode 20. As a matter of clearly avoiding all possible tendency for the discharge or arc to strike upon the annular head 39, I have electrically insulated it from the post 24 and the stationary electrodes 20 in Figure 4. The insulating material 46 is positioned on the top of an annular recess formed by the external surface of the post 24 and the internal surface of the tubular body or shell 38. The open end of the recess is defined between the external surface of the contact 20 and the internal surface of the tubular body 38 and is in communication with the space surrounding the contacts in the vicinity of the arc. The external surface of the stationary contact 20 and the post 24 may be designated as a first portion of the recess, the insulating material 46 as a second portion and the internal surface of the tubular body 38 as a third portion, and these portions in the order named comprise a series of surfaces extending from the stationary contact 20 to the opening in the chamber in which the movable contact operates. The open end of the annular recess is defined by the first and third portions, and the insulating material is between the first and third portions. The flux substantially keeps the arc on the contacts away from the open end of the recess and protects the second portion or insulating material 46 in the recess from the arc to prevent deposits created by the arc from entering the recess and lodging upon the insulating material and establishing a conductive path between the first and third portions. The insulating material 46 may be described as an endless insulating surface transversely disposed of a path extending between the stationary contact and the opening in which the movable contact operates. In other words, the insulating material constitutes a "break" in any path extending between the stationary contact and the opening which the movable contact operates. The flux keeps the arc from entering the recess and effectively sub-divides the recess portion of the chamber from the remaining portion of the chamber between the contacts where the arc occurs.

The openings 41 in the insulating housing 36 and the openings 40 in the annular head 39 respectively define small chambers into which the arc may be drawn by the movable contacts 21 if not immediately extinguished upon the opening of the contacts. The downward movement of the movable contacts in the openings 41 is arrested when the bridging member 47 engages an adjustable stop 19. In my invention, I preferably arrest the movement of the movable contacts in the openings 41, so that the small chambers will be formed above the movable contacts. The operation of the double-break type of contactor as shown in Figure 4 is substantially the same as that described for Figure 1. As shown in the drawings, the posts 24 project from the end wall or panel 26 into the recesses to a point whereby the contacts separate in a region which is closer to the opposite end wall of the recesses containing the small chambers or openings 41.

than to the end wall 26 constituting the top closure end for the annular recesses. Inasmuch as the contacts separate in a region relatively close to the small chambers or openings, the actuating means may quickly withdraw the movable contacts thereinto, whereby the arc is readily extinguished. In the prior art devices of the double-break type, it has been customary to enclose both sets of interrupting electrodes into one chamber. In my invention in Figure 4, I enclose each set of interrupting electrodes in individual metal chambers so that the electrical discharge from one set of interrupting electrodes will not disturb the other set of interrupting electrodes.

In Figure 5 I show a fragmentary view of Figure 4 and illustrate a modification of the magnetic circuit, in that the tubular body 38 in Figure 4 has been replaced by a fore-shortened tubular body 51 having the annular head 39. An insulated tube 52 is interposed between the upper annular end of the fore-shortened tubular body 51 and the insulated block or panel 26. In addition, the circular metal plate 29 is dispensed with and the shoulder 34 on the post 24 rests against a washer 53. The position of the annular head 39 in Figure 5 is substantially the same as that shown in Figure 4 and the path of the flux between the post 24 and the annular head 39 is substantially funnel-shaped as hereinbefore described. The insulated tube 52 constitutes an endless insulating surface transversely disposed of a path extending between the stationary contact and the opening in which the movable contact moves and functions substantially the same as the insulating material 46 in Figure 4 to prevent a conductive path from being formed between the stationary contact and the opening in which the movable contact operates. The flux between the upper annular end of the fore-shortened tubular post 51 and the upper end of the post 24 must pass through non-magnetic material instead of metal as shown in Figure 4. One purpose of showing the invention in the form as illustrated in Figure 5 is to bring out the fact that the electron discharge or arc between the interrupting electrodes may be extinguished even though the magnetic circuit has a high reluctance, since the field strength may be still maintained at a strong value by increasing the ampere turns of the magnetizing coil 44. Hence, the operation of my invention as shown in the form of Figure 5, is substantially the same as that shown in Figure 4. I also find from tests that the annular head 39 may be removed, leaving the lowermost annular end of the tubular body 38 as a pole portion through which the flux passes. The removal of the annular head 39 reduces the efficiency of the magnetic circuit and the brim of the funnel-like flux path is broadened or enlarged. The reduction in the efficiency of the magnetic circuit may be offset by increasing the ampere-turns of the magnetizing coil 44.

In Figure 6 I show a further modified form of the tubular body 38 in that one side of the tube is slotted along the line 54 which has the property of reducing the flow of eddy currents therein. Otherwise, the operation of my invention with the slit tubular body 38 is substantially the same as that with no slit. The annular head 39 and the tubular body 38 may be cut into a number of segments and still come within the purview of my invention.

In Figures 7 and 8 I illustrate another form of

the magnetic circuit in that the annular head 39 is supported by means of a plurality of studs 56 which have at their upper ends reduced stud extensions which pass through openings in the circular metal plate 29 and the insulated block or panel 26 and which have nuts 57 at the uppermost ends thereof for securely anchoring the studs to the circular metal plate 29 and the insulated block or panel 26. The lowermost ends of the studs 56 may be provided with rivets 58 for anchoring the annular head 39 thereto. For simplicity, the Figures 7 and 8 do not illustrate the insulated housing 38. The operation of the device as shown in Figures 7 and 8 is substantially the same as that described hereinbefore.

In Figure 9 I show a modification of the stationary electrode which comprises a hollow tube 60 having a clip 69 attached to the upper end thereof. The hollow electrode is electrically insulated from the circular metal plate 29 by means of an insulating washer 63 positioned between the shoulder 62 and the insulated block or panel 26. The hollow electrode 60 may be secured to the insulated block or panel 26 by means of a nut 66. As illustrated, a plug 61 made of magnetic material is positioned inside of the hollow electrode 60 and may be anchored therein by any suitable means. The plug 61 in combination with the tubular body 38, and the circular metal plate 29 constitutes the magnetic circuit. In Figure 10 I show a modification of the arrangement shown in Figure 9, in that the electrode which is designated by the reference character 66 is solid and is surrounded by a tube 67 of magnetic material. The insulated housing 38 is not shown in Figures 9 and 10. The operation of the two devices shown in Figures 9 and 10 is substantially the same as that described for the previous views of my invention and it is to be pointed out that my invention works equally well regardless of whether the flux at the throat of the fountain-like path is concentrated as it would be in the device in Figure 9 or whether the flux at the throat is distributed in a circle as would be the case with the device shown in Figure 10.

The device shown in Figure 11 is of substantially the same construction as that shown in Figure 9 except that the plug which is inserted within the hollow electrode 60 is made of a permanent magnet material and is designated by the reference character 71. Also, the tubular body 38 may be constructed of a permanent magnetic material and is therefore designated by the reference character 70. The device shown in Figure 12 is substantially the same as the device shown in Figure 10 except that the shell which surrounds the electrode 66 is made of a permanent magnetic material and is designated by the reference character 72. The outside shell 70 in Figure 12 is the same as that shown in Figure 11 and may comprise permanent magnetic material. In the two devices in Figures 11 and 12, both the central pole or the outside enclosure shell 70 may be made of permanent magnetic material, or only one may be made of permanent magnetic material with the other of non-permanent magnetic material, so long as sufficient magnetic flux is set up to control the structure of the electrical discharge or arc between the two interrupting electrodes.

In the case of both the cone-shaped arc and the frustum of the cone-shaped arc, a standing arc discharge is drawn inwardly toward the central portion of the volume of space between the electrodes, the cone arc, however, being drawn inwardly further than the frustum of the cone

arc. As the arc is drawn inwardly from a long or looping uncontrolled arc it becomes shorter and shorter and the resistance of the arc becomes greater and greater, regardless of whether the arc finally takes the form of a cone or finally takes the form of the frustum of the cone. Under a strong magnetic field, the glow appearance and the structure of the arc seems to be the same for both the cone-shaped arc and the frustum of a cone-shaped arc. Also, in both cases of the cone-shaped arc and the frustum of a cone-shaped arc, the end of the arc line which plays on the movable electrode is forced inwardly with a greater force than the end of the arc line which plays on the stationary electrode. However, the cone-shaped arc is forced inwardly towards the central portion of the electrodes with a greater force than the force which tends to force the frustum of a cone-shaped arc inwardly, and thus the interruption of the cone-shaped arc is clearly confined between the electrodes. The frustum of the cone-shaped arc is caused to play upon the electrodes in the region of the marginal edge thereof where the flux lines are the strongest and thus the arc is extinguished very quickly.

With the interruption of alternating current by a single-break contactor, as shown for example in Figure 1, the arc tends to alternate between the cone-shaped arc and the frustum of the cone-shaped arc as the alternating current reverses. When the double-breaking device in Figure 4 is used for interrupting alternating current, the arc at one set of separating electrodes for any single instant is cone-shaped, while the arc at the other set of separating electrodes at the same instant is a frustum of a cone.

The circuit interrupter in Figure 4 is drawn from a practical working device and the size, the proportion of the parts and the spacing between the separated electrodes bear a fixed ratio scale relation to actual devices. Each of the windings 44 in the actual device has approximately 3½ turns the same as shown in the drawings and these turns are sufficient to produce the required field strength to render my device highly effective in interrupting the flow of the large currents. For large load currents, the field will be large, rendering the interruption capacity correspondingly great. For repeated intermittent operations, currents as high as one hundred or more amperes may be successfully interrupted for thousands of operations without perceptible impairment of the contacts.

In this application it is noted that the post 24 in Figures 4, 5 and 7 does not carry the load current. However, the post 24 in these figures is electrically alive. Therefore, in this application and in the claims, the term "electrode" is to be interpreted to include the post or any other part which is electrically alive even though no current flows therethrough.

By means of my magnetic circuit construction, the magnetic field has a central region and an outer annular region with the magnetic flux field in the outer annular region stronger than the field in the central region. The electrodes may be considered as having a central region and an outer annular region which may substantially register respectively with the central region and the outer annular region of the magnetic field. The field in the outer annular region is strong enough and reacts with the flux produced by the arc itself to constrain the arc substantially within the central region when the arc current flows in one direction and to constrain the arc substan-

tially within the outer annular region when the arc current flows in the opposite direction. In any event, regardless of the direction of flow of current in the arc, the arc is magnetically forced toward the central region and is forced inwardly to at least substantially within the outer annular region. In the drawings the distance that the electrodes separate is shorter than the distance that the flux travels in passing from one pole means to the other in my magnetic circuit, although it is to be understood that this relationship may be varied and still come within the purview of my invention.

Although I have described my invention with a certain degree of particularity, it is understood that the present disclosure has been made by way of example and that numerous changes in the details of construction and the combination and arrangement of parts may be resorted to without departing from the spirit and the scope of the invention as hereinafter claimed.

I claim as my invention:

1. In a current interrupting device having at least a first and a second interrupting contact movable relative to each other, said relative movement defining a line of motion, the improvement of apparatus for arresting and extinguishing an arc between the interrupting contacts, said apparatus comprising a shell-like metal housing having an annular rim, a post element projecting in the housing, means for mounting the first contact on the post element, said second contact being movable in the housing beyond the annular rim and engaging the first contact, said post element and said housing comprising a magnetic circuit having opposite pole portions forming an air gap through which flux passes, said post element constituting one pole portion and said annular rim constituting the other pole portion, the separation of the electrodes occurring in said air gap within the housing whereby an arc between the separating contacts is controlled by said flux, said opposite pole portions being so disposed with reference to each other that a line drawn therebetween is other than a right angle with respect to said line of motion.

2. In a current interrupting device having at least a first and a second interrupting contact movable relative to each other, said relative movement defining a line of motion, the improvement of apparatus for arresting and extinguishing an arc between the interrupting contacts, said apparatus comprising a post element and an annular member surrounding the post element, means for mounting the first contact on the post element, said post element and said annular member comprising a magnetic circuit having opposite pole portions forming an air gap through which flux passes, said post element constituting one pole portion and said annular member constituting the other pole portion, the separation of the contacts occurring in said air gap within the annular member whereby an arc between the separating contacts is controlled by said flux, said opposite pole portions being so disposed with reference to each other that a line drawn therebetween is other than a right angle with respect to said line of motion.

3. In combination, a switch comprising a stationary contact and a movable contact arranged to interrupt a circuit, said stationary contact having an abutting surface against which the movable contact engages, a magnetic circuit comprising first and second magnetic poles between which flux passes, said magnetic circuit including a post element having an end portion con-

stituting said first magnetic pole and an outer element having a portion disposed laterally of the post element and constituting said second magnetic pole, said first magnetic pole being disposed substantially in alignment with the contacts and being positioned on the side of said abutting surface of said stationary contact which is opposite from said movable contact, and insulating means having a chamber for housing the stationary contact, the post element and the outer element, said insulating means having an opening connecting the chamber to the outside thereof, said movable contact being movable in said opening, said chamber having an internal wall for supporting the said outer element.

4. In combination, a switch comprising an insulating housing having a chamber, said housing having a first part and a second part connected together, said second part having a recess with an internal wall comprising a portion of said chamber, said second part also having an opening connecting the recess to the outside thereof, a stationary contact and a movable contact arranged to interrupt a circuit in the chamber, said movable contact being movable in said opening, a magnetic circuit comprising first and second magnetic poles between which flux passes, said magnetic circuit including a post element connected to the first part of the housing and projecting into the recess and an outer element disposed laterally of the post element and supported by the internal wall of the recess, said post element having an end portion supporting the stationary contact in the recess and constituting said first magnetic pole and said outer element having a substantially annular portion constituting said second magnetic pole.

5. In combination, a switch comprising an insulating housing having a chamber, a stationary contact and a movable contact arranged to interrupt a circuit in the chamber, said chamber having an open end to receive the movable contact, said housing comprising an insulating support member and an insulating body member having an annular internal wall constituting a portion of the chamber, a first element composed of magnetic material mounted on the insulating support member and having a projection portion extending into said chamber toward the open end thereof, said projection portion supporting the stationary contact upon the end thereof and constituting a first magnetic pole, a second element composed of magnetic material disposed between the first element and the annular internal wall of the chamber and having a portion constituting a second pole, wall means in the chamber defining a surface having a first portion, a second portion and a third portion, said portions in the order named comprising a series of surfaces extending from the stationary contact to the open end of the chamber in a region of the vicinity of the movable contact, said first portion including the external surface of the first element, said third portion including the internal surface of the second element and said second portion comprising insulating material and being disposed intermediate the first and third portions, said wall portions defining an annular recess having an open end communicating with the space surrounding the contacts in the vicinity of the arc, said first and third wall portions defining the said open end of the recess with the second wall portion disposed in the recess, and winding means surrounding the first element for passing flux between said poles, said flux substantially keeping the arc away

from the said open end of the recess and protecting the second portion in the recess from the arc to prevent deposits created by the arc from entering said recess and lodging upon the second portion and establishing a conductive path between the first and third portions.

6. In combination, a switch comprising an insulating housing having a chamber, a stationary contact and a movable contact arranged to interrupt a circuit in the chamber, said chamber having an open end to receive the movable contact, said housing comprising an insulating support member and an insulating body member having an annular internal wall constituting a portion of the chamber, a first element composed of magnetic material mounted on the insulating support member and having a projection portion extending into said chamber toward the open end thereof, said projection portion supporting the stationary contact upon the end thereof and constituting a first magnetic pole, a second element composed of magnetic material disposed between the first element and the annular internal wall of the chamber and having a portion constituting a second pole, wall means in the chamber defining a surface including the external surface of one of said elements and having a first portion, a second portion and a third portion, said portions in the order named comprising a series of surfaces extending from the stationary contact to the open end of the chamber in a region of the vicinity of the movable contact, said second portion comprising insulating material and being disposed intermediate the first and third portions, said wall portions defining an annular recess having an open end communicating with the space surrounding the contacts in the vicinity of the arc, said first and third wall portions defining the said open end of the recess with the second wall portion disposed in the recess, and winding means surrounding the first element for passing flux between said poles, said flux substantially keeping the arc away from the said open end of the recess and protecting the second portion in the recess from the arc to prevent deposits created by the arc from entering said recess and lodging upon the second portion and establishing a conductive path between the first and third portions.

7. In combination, a switch comprising a stationary contact and a movable contact arranged to interrupt a circuit, a housing having a large chamber with an enclosure wall for housing the contacts, a post element in the housing supporting the stationary contact, said large chamber having on one side thereof a recess and having on the other side thereof a small chamber, said small chamber connecting the large chamber to the outside of the housing and comprising an opening in which the movable contact operates, means for arresting the interrupting movements of said movable contact in said small chamber, said recess being defined in part by said post element and said stationary contact and having an endless insulating surface which extends transversely across a path extending between said stationary contact and said opening in which the movable contact operates, and magnetic circuit means including said post element and a magnetizable winding surrounding the post element for substantially keeping the arc from said recess to prevent deposits created by the arc from entering said recess and lodging upon the endless insulating surface thereof.

8. In combination, a switch comprising a sta-

tionary contact and a movable contact arranged to interrupt a circuit, said stationary contact having an abutting surface against which the movable contact engages, a magnetic circuit comprising first magnetic pole means and a second magnetic pole means between which flux passes, said magnetic circuit including a post element having an end portion for supporting the stationary contact and an outer element disposed laterally of the post element and having an opening in which the movable contact operates, said end portion of said post element including the first magnetic pole means and said outer element including the second magnetic pole means, said first magnetic pole means being disposed substantially in longitudinal alignment with the contacts and being longitudinally spaced from the second magnetic pole means, whereby a line drawn between the magnetic pole means is at an angle other than a right angle to the longitudinal axis of the post element.

9. In a circuit interrupter, a magnetic circuit having first pole means and second pole means between which flux passes, said first pole means including an elongated element having a longitudinal axis and having an end portion provided with an end surface constituting a first pole face and said second pole means including substantially an annular member having an annular surface constituting a second pole face, said annular surface being longitudinally spaced from the said end surface, whereby a line drawn from said first pole face to said second pole face is other than a right angle with respect to the longitudinal axis of the elongated element, a stationary contact mounted on the end portion of the elongated element, and a movable contact adapted to engage the stationary contact, said second pole means being electrically insulated from the stationary contact means, said annular surface surrounding the movable contact in the closed circuit position and being so longitudinally spaced with respect to the stationary contact that said annular surface is intermediate said contacts in the open circuit position.

10. In combination, a switch comprising a stationary contact and a movable contact arranged to interrupt a circuit, a magnetic circuit means for producing a field to extinguish an arc between the contacts, said magnetic circuit means comprising central and outer members defining substantially coaxial pole pieces between which flux passes, the separation of the contacts occurring between said pole pieces, said central pole piece supporting said stationary contact and being foreshortened with respect to the outer pole piece, whereby a line drawn between said pole pieces is other than a right angle with respect to the axis of the central pole piece.

11. In combination, a switch comprising an insulating housing having a chamber, a stationary contact and a movable contact arranged to interrupt a circuit in the chamber, said chamber having an open end to receive the movable contact, said housing comprising an insulating support member and an insulating body member having an annular internal wall constituting a portion of the chamber, a first element composed of magnetic material mounted on the insulating support member and having a projection portion extending into said chamber toward the open end thereof, said projection portion supporting the stationary contact upon the end thereof and constituting a first magnetic pole, a second element composed of magnetic material disposed in the

chamber and having a portion constituting a second pole, wall means in the chamber defining a recess including the external surface of one of said elements and the annular internal wall of the insulating body member, said recess extending from the stationary contact toward the insulating support member, and winding means surrounding the first element for creating flux between the poles.

12. A circuit interrupter comprising an insulating housing having a chamber with an annular internal wall, a post element of magnetic material supported by the housing and projecting into the chamber, cooperative contacts to be engaged and disengaged in said chamber and comprising 15

tact member, said housing having an opening in which the movable contact member moves, said stationary contacts being mounted on the end of the post element projecting into the chamber, said post element and said stationary contact member defining in combination with the internal wall of the chamber an annular recess having an open end in communication to the outside of the housing through said opening in which the movable contact moves, magnetizable winding means mounted in the open recess and around the post element, and a member constituting a shell of magnetic material mounted in the recess and supported by the internal wall of the housing.

GERHARD W. PETERS.
